UNITED STATES PATENT OFFICE.

GORDON BYRON FIELDS, OF JACKSONVILLE, FLORIDA, ASSIGNOR TO MERGENTHALER LINOTYPE COMPANY, A CORPORATION OF NEW YORK.

QUAD-BLOCK FOR SLUG-CASTING MACHINES.

1,231,870.

Specification of Letters Patent.

Patented July 3, 1917.

Application filed August 4, 1915. Serial No. 43,533.

To all whom it may concern:

Be it known that I, GORDON BYRON FIELDS, a citizen of the United States, residing at Jacksonville, in the county of Duval and State of Florida, have invented certain new and useful Improvements in a Quad-Block for Slug-Casting Machines, of which the following is a specification, reference being had therein to the accompanying drawing.

My invention relates to slug casting machines, such as linotype machines of the general organization represented in United States Letters Patent to O. Mergenthaler, No. 436532, wherein a slug or linotype is cast in a slotted mold against an assembled matrix line, which produces the type characters thereon.

Ordinarily the matrix line is composed of a series of individual matrices which circulate through the machine, but at other times, it is made up of a single non-circulating matrix, known in the art as a "quad block", and used particularly for the production of quads, rules, border slugs, and the like. As now constructed, the quad block consists of a long body portion, similar in cross section to an ordinary matrix, and having in its front face an integral strip or plate containing formative cavities corresponding to the characters which are to be produced. When it is desired to cast a different form of slug, or a slug with a different arrangement of the characters, the strip is removed and replaced by another containing the proper formative cavities. By reason of the integral nature of the matrix strips, it is necessary to punch a special one for each different slug to be produced, the number of strips thus multiplying to a very considerable extent. The expense, annoyance and delays occasioned by this practice becomes quite pronounced in connection with "rule" or "tabular" work, which require many different arrangements and spacings.

My present invention is intended primarily to avoid the above objections, and to this end I provide one or more sets of short interchangeable matrix sections which can be set into the quad block to build up the matrix. These sections are made of various sizes and widths, so that by their interchange different formative cavities may be brought into use and located in any suit-

able position to meet the conditions demanded. In this way, the same sections may be employed for the production of slugs of various designs and descriptions, thereby saving much time and expense which would otherwise be incurred in the preparation of special plates.

In the accompanying drawing, I have shown the formative cavities as straight depressions or cuts for the production of slugs with plain ruling, but it should be understood that my invention is not restricted in this respect, as it may readily be adapted to various other classes of work which require the use of slugs with other kinds of printing characters. Furthermore, I have shown my invention merely in preferred form and by way of example, and it should be noted that many changes and variations may be made therein which will still be comprised within its spirit. Generally speaking, I desire it to be understood that I do not limit myself to any specific embodiment or adaptation, except in so far as such limitations are specified in the claims.

Referring to the drawing:

Figure 1 is a perspective view of a quad block equipped with my improved matrix sections;

Fig. 2 is a transverse section through the mold of a linotype machine and the quad block, which is shown in operative relation thereto;

Fig. 3 illustrates an assembled series of slugs produced in accordance with my invention; and

Figs. 4 and 5 are detail-views of the matrix sections.

The quad block A is of the usual construction, being formed in its front face with the longitudinal groove or recess A¹ of dove-tail shape. Located in the groove A¹ are a series of matrix sections B and a long strip or bar C, these parts presenting in their assembled condition a continuous matrix of substantially the same form as the integral matrix plate now in common use. The strip C engages in the lower portion of the groove A¹, while the sections B are supported thereon side by side with their upper ends engaging in the upper portion of the groove. In this way, the sections are held securely against forward or facewise displacement from the block A, while they are capable of being withdrawn edgewise

for interchange, in the manner indicated in Fig. 1.

Fig. 3 illustrates an assembled series of slugs D such as it is the object of my invention to produce. Each of these slugs is provided along its edge with a longitudinal rib or ruling surface D¹, and a series of transverse ribs or ruling surfaces D², the latter being arranged on the successive slugs of the series so as to stand in transverse alignment. When a print is taken from such slugs, there will be produced a blank form consisting of a series of longitudinal lines, and a series of intersecting transverse lines, such as is desired for ledger pages, baseball scores, etc.

The longitudinal rib D¹ is produced by a horizontal cut or depression B² formed by beveling the upper edge of the strip C and the lower ends of the matrix sections B; while the transverse ribs D² are produced by vertical notches or depressions B¹ formed in some of the matrix sections, the others being left plain or smooth to produce the blank spaces between the ribs.

In casting, the quad block is supported in operative relation to a mold E, as shown in Fig. 2, and with the formative cavities or depressions B¹ and B² standing opposite the mold slot E¹, so that the molten metal may flow into such cavities and produce the ruling surfaces D¹ and D² on the slug, as before described.

It is to be understood that there is provided a complete set of the matrix sections B varying in width according to a given typographic unit, which in this country is the "em." Accordingly, any desired spacing or arrangement of the ruling surfaces D² or sections and assembling them in the proper position in the block. Thus, in Fig. 1 the sections are shown of various widths and assembled in such relation as to produce the slug indicated in Fig. 3. If it should be desired to vary the location of the ruling surfaces D² upon the slugs so as to secure a different spacing of the transverse lines of the blank forms to be produced, this may be accomplished by rearranging the sections in the block or by selecting and substituting other sections of different widths. Obviously, there is no particular limit to be set for the width of an individual matrix section, as this will depend principally upon the class of work involved. For example it is frequently the case that the blank spaces between the columns are of uniform extent, and in such event it might be desirable to employ a single matrix section of corresponding width. However, this is not at all essential, as a number of the shorter sections could be employed with the same effect. The whole requirement in this connection is that the width of the matrix sections be

gaged according to the standard typographic unit, whether a fraction or a multiple of such unit. In some instances, the spacing or location of the depressions B¹ will not depend entirely upon the width of the individual sections, but rather upon the different setwise positions of the depressions in the respective sections. Thus, as shown in Fig. 5, two of the matrix sections B are of the same width but have their notches or depressions located in different relative positions thereon, it being noted also that one of the depressions is of larger size than the other so as to produce a thicker or heavier ruling surface.

In printing some blank forms, it may become necessary or desirable to vary the spacing between the longitudinal lines in addition to or independently of that between the transverse lines. For this purpose, there is provided a further set of matrix sections similar to the sections B but of less length or height. Two such sections, marked F, are shown in Fig. 5, one being plain or smooth and the other having a slot or depression F¹ of about half the extent of the depressions B¹ of the sections B. In making use of the sections F, it will be understood that the co-operating strip C will be of increased width to correspond. In like manner, other sets of matrix sections may be provided to secure different spacings of the printing lines.

For certain kinds of work, it may be desired to cast slugs without the longitudinal ruling surface, but merely with the transverse ruling surfaces. In this event, the beveled or chamfered surfaces along the ends of the matrix sections B and edge of the strip C may be eliminated, or instead the matrix sections B may be made of such size or height as to fill the notch A¹ completely. Various other like modifications may be made, but they will readily suggest themselves to those skilled in the art and require no specific mention here.

While in the present instance the matrix sections have been designed for the specific purpose of making up the matrix strip of a quad block, it should be noted that according to certain broad features of my invention, the sections may be made of other form—for instance, like the ordinary matrices used in the linotype machine. Thus, I believe it to be new in the art to provide a plurality of such matrix sections of any form bearing the same character and varying in width so that when the sections are assembled side by side in line, a definite and predetermined arrangement of the matrix characters is secured. Further, I believe it to be new to provide a plurality of matrix sections which vary in width relatively and irrespective of the size or width of the characters which they contain.

Having thus described my invention, its construction and mode of operation, what I claim and desire to secure by Letters Patent of the United States, is as follows:

- 5 1. A quad block comprising an integral elongated body portion containing in its operative face a series of individual matrix sections arranged side by side and varying in width according to a given typographic unit irrespective of the size of the matrix characters to secure a definite spacing of said characters in the length of the block. 65
- 10 2. A quad block comprising an integral elongated body portion containing in its operative face a series of individual matrix sections arranged side by side and varying in width according to a given typographic unit irrespective of the size of the matrix characters to secure a definite spacing of said characters in the length of the block. 70
- 15 3. A quad block containing in its operative face a series of individual matrix sections arranged side by side in contact to make up a continuous matrix strip and varying in width according to a given typographic unit to secure a definite spacing of the matrix characters in the length of the block, said sections being replaceable by others of different widths to vary the spacing of the matrix characters. 80
- 20 4. A quad block comprising an integral elongated body portion containing in its operative face a series of individual matrix sections arranged side by side in contact to make up a continuous matrix strip and varying in width according to a given typographic unit to secure a definite spacing of the matrix characters in the length of the block, said sections being replaceable by others of corresponding width but of different height, for the purpose described. 85
- 25 5. A quad block comprising an integral elongated body portion containing in its operative face a matrix made up in part of a longitudinally arranged strip and in part of a series of transversely arranged sections. 90
- 30 6. A quad block comprising an integral elongated body portion containing in its operative face a matrix made up of a longitudinally arranged strip and a series of transversely arranged sections, the edge of said strip and the contiguous ends of said sections being beveled or chamfered so as conjointly to provide a straight horizontal depression for the production of a slug with a longitudinal rib or ruling surface. 95
- 35 7. A quad block comprising an integral elongated body portion containing in its operative face a series of individual matrix sections having characters arranged in different setwise positions on their respective sections, for the purpose described. 100
- 40 8. A set of matrix sections constructed to make up the matrix strip of a quad block, the said sections having a common matrix character and varying in width throughout the set irrespective of the size of said character, for the purpose described. 105
- 45 9. A plurality of sets of matrix sections constructed to make up a matrix strip of a quad block and each section being formed with a matrix character which extends practically throughout the height thereof, the sections of one set being of different height from those of another set to vary the extent of their respective matrix characters. 110
- 50 10. A matrix section beveled at one end and formed with a slot or depression cutting into said bevel, so as to produce on a slug connected ruling surfaces. 115
- 55 11. A common set of interchangeable matrix sections adapted to be assembled side by side and varying in width according to a given typographic unit irrespective of the size or width of the characters they contain. 120
- 60 12. A common set of interchangeable matrix sections adapted to be assembled side by side and varying in width according to a given typographic unit irrespective of the size or width of the characters they contain. 125
- 65 13. A plurality of matrix sections containing the same character, the said character being located in different setwise positions on the respective matrix sections. 130
- 70 14. A plurality of matrix sections containing the same character, the said sections varying in width according to a given typographic unit, and having their characters located in different relative positions on the respective sections. 135
- 75 15. A common set of interchangeable matrix sections adapted to be assembled side by side and containing the same matrix character, the said sections varying in width according to a given typographic unit irrespective of the size of said matrix character. 140

In testimony whereof, I have affixed my signature in presence of two witnesses.
